UNITED STATES PATENT OFFICE.

DAVID E. APPLEGATE, OF CHATSWORTH, NEW JERSEY.

CRANBERRY SEPARATOR.

Application filed December 3, 1927. Serial No. 237,432.

My invention relates to new and useful improvements in a cranberry separator, and has for its primary object to provide means for readily and quickly sorting or separating small, soft, rotten or low-grade berries from the better grade or good ones.

Another object of the invention is to provide, in a device of this character, a separator of endless belts, alternate ones of which travel in opposite directions and zig-zag lanes or courses to guide the berries cross-wise of the belts, means to sort the berries while passing over the belts, and means to remove the unsound berries from certain lanes or courses after which they will be carried to a point of disposal by the belts.

A further object of my invention is to provide a machine into which the cranberries may be fed in large quantities and then automatically distributed to a number of lanes or courses and through which they move by belts operating in opposite directions during which time the unsound berries are sorted from the good ones and fed to a point of disposal while said good berries are propelled forwardly to another point of disposal as to a packing table.

A still further object of my invention is to provide in a cranberry picker, a unique arrangement for sorting unsound berries from good ones, which consists particularly of a number of belts running under lanes or courses arranged in pairs, the lanes of each pair being in communication or what I prefer to term, being separated from each other by a partial barrier so that the unsound berries will be moved or forced from one lane to the other of the pair due to the action of the belts, and means to cause the unsound berries to be directed to one point of disposal and the good berries to another point of disposal.

With these ends in view, this invention consists in the details of construction and combination of elements hereinafter set forth and then specifically designated by the claims.

In order that those skilled in the art to which this invention appertains may understand how to make and use the same, I will describe its construction in detail, referring by numerals to the accompanying drawings forming a part of this application, in which:

Fig. 1, is a side elevation of a cranberry sorter constructed in accordance with my invention.

Fig. 2, is a plan view thereof.

Fig. 3, is an end view of the same on a slightly enlarged scale.

Fig. 4, is an enlarged fragmentary plan view to more plainly illustrate constructional details conventionally shown in Fig. 2.

Fig. 5, is a section on the line 5—5 of Fig. 4.

Fig. 6, is a section on the line 6—6 of Fig. 4.

Fig. 7, is a further enlarged fragmentary plan view of the feed end and the distributors of the machine.

Fig. 8, is an enlarged sectional view on the line 8—8 of Fig. 4.

Fig. 9, is an enlarged sectional view on the line 9—9 of Fig. 4, with the belt operating mechanism shown in elevation.

Fig. 10, is an enlarged sectional view on the line 10—10 of Fig. 4.

In carrying out my invention as herein embodied, 15 represents a suitable frame including uprights 16 to which are suitably fastened the side pieces 17 and to said sides 80 pieces are connected the tops 18.

As herein illustrated, the frame of the machine is made up of a number of units, each unit including the uprights, sides and a top, but it is to be fully understood that any other construction could be used.

The units thus provided are somewhat like tables and are arranged side by side in a unitary structure with each succeeding unit top or table in a lower plane than the preceding one.

At each end of each unit is supported a cross piece 19 on the endmost uprights of each unit, and at other places, if desirable or necessary, according to the length of the units and on said cross pieces are mounted stationary beams 20, two of which are associated with each unit for a purpose to be presently described.

The first unit or table is to be known as the distributing table over the surface of which runs one portion of an endless belt 21 in the direction of the arrows in Figs. 2 and 4, and in order to propel this belt, it is mounted upon pulleys 22, 22', one at each end of the machine, and at the proper elevation, each pulley being mounted upon a shaft 23, journaled in suitable bearings carried by the distributing table unit.

The next succeeding unit has a belt 24 running over it and carried by pulleys 25, 25', one at each end of said succeeding unit, each

pulley being mounted upon a short shaft 26, suitably journaled in certain of the uprights thereof. The unit over which the belt 24 runs might well be termed the first sorting unit and the balance of them would be known as the second, third, fourth, etc.

Over the second sorting unit, runs a belt 27 mounted upon pulleys 28, 28' one at each end of the unit, each of said pulleys being mounted upon a short shaft 29, suitably journaled in certain of the uprights in the second sorting unit.

One pulley of each unit is an idler, as indicated by the numerals 22', 25' and 28', while the other pulley of each unit is a driver as the one indicated by the numerals 22, 25 and 28, and the shaft of each driving pulley receives its motion from a suitable source of power through the medium of a sprocket 30, or its equivalent mounted on its shaft, as 26, and from which runs a chain 31 also engaging another sprocket 32 mounted on a power shaft 33 provided with a pulley 34, or other equivalent means, by which motion may be transmitted to the power shaft 33, from a suitable prime mover. It is to be understood that there is a power shaft at each end of the machine for driving alternate belts, and in any well known manner, the driving pulleys at one end of the machine, operate in a reverse direction to those at the outer end of the machine, so that said alternate belts move in opposite directions.

To one or both of the beams 20 associated with the distributing unit or table are secured guide panels 35 by means of suitable fastening devices 36 so as to depend from the beams with their lower edges in close proximity to the surface of the belt 21.

Said guide panels are arranged obliquely to the path of travel of the belt and extend from the inner edge of the belt outwardly toward the opposite or outer edge of the belt and in a direction opposite to the path of travel of said belt with the outer or free ends of the preceding panels terminating short of the succeeding panels so that objects on the belt adjacent the inner edge thereof will contact with a panel prior to such objects on other parts of the belt, thus distributing said objects to the several distributing lanes or courses 37 formed between the panels.

To the beams 20 of the first sorting unit are secured stationary barriers 38 in suitable spaced relation by means of fastening devices 39 so that said barriers depend from the beams with their lower edges in close proximity to the belt 24.

These barriers are also in the form of panels and are arranged obliquely to the path of travel of the belt and extend entirely across said belt projecting from the edge adjacent the distributing unit in the general direction of the travel of the belt to the opposite edge of the latter.

Between the barriers 38 are located parallel partial barriers 40 also in the form of panels, and these partial barriers are dependably fastened to adjustable beams 41, the partial barriers being suitably cut out so as to pass about the beams 20 and for connection to the beams 41 to which they are secured by fastening devices 42. The adjustable beams 41 are slidably mounted over up-standing bolts 43 and held in different adjusted positions by means of nuts 44 and 45 which have threaded engagement with the bolts, and which latter are suitably mounted on the cross pieces. By adjusting the beams 41 up or down, the spaces between the lower edges of the partial barriers 40 and the belt may be varied.

Adjacent barriers and partial barriers form lanes or courses, one set of which will be termed common lanes and designated by the numeral 46 and the other set will be termed unsound berry lanes and designated by the numeral 47, and adjacent ones of these lanes are in communication through the spaces beneath the partial barriers and the common lanes are in communication with the distributing channels 37, the unsound barrier channels being blocked from the distributing channels by walls 48.

At the other end of the lanes or courses 46 and 47, they communicate with similar lanes or courses of the next succeeding sorting unit, and in said succeeding unit, the panels or barriers are arranged obliquely, but at an angle opposite to those of the preceding ones 100 and so on, throughout the entire machine so that the berry lanes or courses are of zig-zag formation.

As before stated, the barriers of the first sorting unit run the entire width of the belt, but in the succeeding units, these panels are so arranged that their forward ends terminate short of the edge of the adjacent edge of the belt and to said forward ends of the stationary barriers is secured a stringer 49 so as to provide between it and a side of the frame, an unsound berry channel 50, which runs longitudinally of the belt to one end of the machine. There is one of these channels between all adjacent sorting units, but not between the distributing unit and the first sorting unit. These channels are in communication with the unsound berry lanes or courses, but the common berry lanes or courses of adjacent units are in direct communication through the medium of bridges 51 which span the channels 50 so that berries traveling through the common lanes of one sorting unit will pass over a bridge and into the common lanes of the succeeding sorting unit and said berries are caused to travel through these lanes by the action of the belts on which they are resting.

Because of the oblique arrangement of the panels 35 of the distributing unit and the 130

like arrangement of the berries of the sorting units, any berries placed upon the belt 21 of the distributing unit will be moved through the distributing courses 37 into the several 5 common berry lanes 46 of the first sorting unit where they will be caused to travel through said common berry lanes by the action of the belt 24. During the travel of the berries through the common berry lanes, they 10 will be moved, rolled or agitated, so that a number of them and possibly all of them will be brought into contact with the partial barriers 40. When thus brought into contact with the partial barriers, any unsound berries such as those that have rotted or become 15 soft from bruising, or have become spongy due to freezing, will be forced beneath or actually pulled by the belt under the partial barrier and into the unsound berry lanes 47, 20 but because of the succeeding complete barrier such unsound berries are caused to travel through the unsound berry lanes until they reach the ends where they will drop off into one of the unsound berry channels 50 and be 25 carried to an end of the machine for any disposition desired. The sound or good berries, and in fact any unsound ones that may not have come in contact with the partial barrier, will be moved along the common berry lanes 30 and due to the ones behind, foremost berries will be forced over the bridges into the common berry lanes of the succeeding sorting unit where the same actions above described will take place. As any number of these sorting 35 units may be used, it is probable that if four or five of such units are provided in a machine, all of the unsound berries will be sorted from the sound ones before the latter reach the separating table over which runs the belt 40 52 for carrying the berries toward a chute 53 by which said berries will be finally guided into suitable receptacle such as a barrel, crate or the like. During the movement of the berries along the belt 52, discolored or unripe 45 ones may be separated from the others by persons standing along one side of the machine.

The unsound berries which drop into the channels 50 are carried toward one end of the 50 machine by the belt on which they drop where they will enter a chute 54 from which they will drop on to a refuse belt 55 and be carried to a dump or other point of disposal. The belt 55 runs over suitable pulleys, one of which 55 is shown at 56 as being mounted on a shaft 57, journalled in suitable bearings carried by the stanchions 58, and on said shaft 57 is a worm gear 59 meshing with a worm wheel 60 fixed to the power shaft 33.

60 If found desirable, the cross pieces 19 may be made to overlap as shown in Fig. 6 with a filter 61 between the overlapping ends all of which are fastened together by securing devices 62, such as bolts.

65 If a crop of very large berries is to be

sorted, the partial barriers may be adjusted to provide larger spaces between their lower edges and the belts by backing off the nuts 44 and screwing the nuts 45 upwardly on their respective bolts 43, but if the berries are 70 of a small size, then the nuts are adjusted in a reverse direction which will lower the adjustable partial barriers and provide smaller 75 spaces between their lower edges and the bolts.

From the foregoing description, it is to be particularly noted that a large quantity of berries may be placed upon the distributing belt 21 after which the berries will be automatically distributed to the several common 80 berry lanes and the unsound ones quickly sorted or removed from the good ones, the latter continuing to a point of proper disposal while the unsound ones are discarded. By the use of such a device, a great deal of 85 handling is eliminated and a greater number of berries can be sorted in a given length of time and at less expense than by the methods now employed. Further, the sorting is more thorough because the appearance of the berry 90 has nothing to do with its removal as an unsound one, as the method of sorting depends upon whether or not the berry is soft, spongy or small.

95 Of course I do not wish to be limited to the exact details of construction as herein shown, as these may be varied within the limits of the appended claims without departing from the spirit of my invention.

Having thus fully described my invention, what I claim as new and useful is:

100 1. A cranberry separator comprising a plurality of belts, alternate ones of which travel in opposite directions, means to direct berries obliquely cross-wise of said belts, said means including alternate complete and partial barriers, the latter being spaced above the belts, the action of said belts causing soft, spongy, unsound berries to pass beneath the partial barriers and separate them from the sound ones, means to convey the unsound berries to a place of disposal, and other means to 105 convey the sound berries to another place of disposal.

110 2. The structure set forth in claim 1, where- in the partial barriers are adjustable to permit of regulating the space between their lower edges and the belts.

115 3. A cranberry separator comprising a plurality of belts, each succeeding one of which is in a lower plane than the preceding one and alternate ones traveling in opposite directions, common berry lanes disposed obliquely over the belts, unsound berry lanes 120 paralleling the common berry lanes and arranged in pairs and in communication throughout their length by a passageway of less height than sound berries passing through the separator, the action of the belts causing 125 the berries to pass from the common berry 130

lanes to the other lanes and propelling all of the berries through their respective lanes, channels formed length-wise of the majority of the belts, bridges over said channels to convey the berries in the common lanes over one belt to the common lanes over another belt, the berries in the unsound berry lanes dropping on to the succeeding belt within a channel by which they will be conveyed to an end of the 10 separator for disposal and means to convey the sound berries which have passed through the common berry lanes to another point of disposal.

4. The structure set forth in claim 3 in connection with means for distributing a quantity of the berries to the various common lanes.

5. A berry separator comprising a plurality of conveying means, alternate ones of 20 which travel in opposite directions, means co-acting with the conveying means to cause berries to travel obliquely across said convey-

ing means, and a third means to cause unsound berries to separate from the sound ones.

6. The structure set forth in claim 5 in connection with means to feed berries to the second named means and other means to remove the unsound berries after being separated from the sound ones.

7. A cranberry separator comprising common berry lanes and unsound berry lanes arranged in pairs, the common berry lane of each pair being in communication throughout its length with its respective unsound berry lane through a restricted space under a party wall, and means passing beneath lanes, obliquely thereof to propel berries through said lanes and to draw soft, spongy ones through the restricted space from the common berry lane to the other lane.

In testimony whereof, I have hereunto affixed my signature.

DAVID E. APPLEGATE.
